US0D1016785S

(12) **United States Design Patent** (10) **Patent No.:** **US D1,016,785 S**
(45) **Date of Patent:** **** Mar. 5, 2024**

(54) **EAR BUD**

(71) Applicant: **Inova Design Solutions Ltd**, London (GB)

(72) Inventors: **Leon Marsh**, London (GB); **Cianan O'Dowd**, London (GB); **Matthew Clements**, London (GB)

(73) Assignee: **INOVA DESIGN SOLUTIONS LTD**, London (GB)

(**) Term: **15 Years**

(21) Appl. No.: **29/724,643**

(22) Filed: **Feb. 18, 2020**

(30) **Foreign Application Priority Data**

Aug. 19, 2019 (EM) 006739173

(57) **CLAIM**

The ornamental design for an ear bud, as shown and described.

DESCRIPTION

FIG. 1 is a perspective view of an ear bud showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the ear bud that form no part of the claimed design.

1 Claim, 7 Drawing Sheets
